UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

PROCESS AND APPARATUS FOR ASCERTAINING THE HARDNESS OF METAL PARTS.

1,354,216.

Specification of Letters Patent. Patented Sept. 28, 1920.

Application filed August 21, 1918. Serial No. 250,862.

To all whom it may concern:

Be it known that I, EUGÈNE SCHNEIDER, citizen of the French Republic, residing at 42 Rue d'Anjou, Paris, France, have invented certain new and useful Improvements in Processes and Apparatus for Ascertaining the Hardness of Metal Parts, of which the following is a specification.

Hitherto, for the purpose of ascertaining the hardness of a metal part, and more particularly the hardness of shells or other hollow articles, use is generally made of the method known as Brinell's method which consists substantially in indenting the surface of the article to be tested, at a varying point, by means of a hard body such as a steel ball, and in measuring the dimensions of the indentation.

Experience and observations of the applicant have shown that this method of ascertaining the hardness is not satisfactory and gives only very incomplete results; for instance in particular this method does not give any indication relating to the greater or less degree of homogeneity of the metal in the mass of the article the hardness of which it is desired to ascertain.

The present invention has for its object to provide an improved process and apparatus which will allow of remedying the above drawbacks in a manner which will be sufficient for practical purposes.

The improved process consists essentially in producing one or more indentations by simultaneous and practically equal pressures in two opposite surfaces of the article. The simultaneous pressures are therefore caused to act under identical conditions of pressure, temperature and duration of indentation, and at two opposite points including between them the thickness of the article, the hardness of which it is desired to ascertain before tempering, after tempering, or at any other moment of a heat treatment. The examination of the simultaneous indentations will furnish, in addition to the absolute indication given by their dimensions, a comparison between the hardness at two opposite points, and consequently a very valuable indication as to the greater or less degree of homogeneity of the metal in the region where the test has been made.

An apparatus for carrying into effect this

improved process consists essentially of a kind of tongs or pincers whose shorter arms 55 form jaws adapted to receive alternately an indenting body, such as a ball, and a device for reproducing said indentation, such as a die containing a lump of lead or other plastic material.

The invention comprises an apparatus constituting a practical form of the said pincers for ascertaining the hardness of shells and other hollow articles.

Figure 1 is a sectional elevation of an apparatus for ascertaining the hardness of an article of any desired profile.

Fig. 2 is a partial section on the line 70 II—II of Fig. 1.

Figs. 3 to 6 illustrate an apparatus for applying the improved process for the purpose of ascertaining the hardness of a hollow article, such as for instance a shell.

Fig. 3 is a side elevation.

Fig. 4 is a plan.

Fig. 5 is a vertical section on the line 75 V—V of Fig. 4.

Fig. 6 is a section on the line VI—VI of 80 Fig. 3.

Figs. 7 and 8 are respectively a vertical section and a partial plan of a modification of the apparatus.

Referring first to Figs. 1 and 2, A is an axle mounted in a suitable support B; on 85 this axle are rotatably mounted the two members C—C¹ and D—D¹ of a tongs or pincers. At the end of each of the shorter arms C, D, there may be mounted a removable indenting device consisting for instance 90 of a ball e held in a small holder E adapted to be screwed in a corresponding internal screw-thread in the arm of the pincers. When the simultaneous indentations have been impressed into the article F to be tested, it is an easy matter to remove the ball 95 holders E—e and to replace them by dies, that is to say, holders similar to E but bearing a plate of plastic material, such as lead.

The simultaneous and practically equal pressures applied at two opposite points f, f¹, that inclose between them the thickness of the article F, are produced by moving the ends of the longer arms C¹, D¹ of the pincers closer together. This movement 105 may be effected for instance by means of the mechanism shown.

G, H are sleeves journaled by means of

trunnion pins g , h , respectively between forks formed on the ends of the arms C^1 , D^1 . The sleeve G is internally screw-threaded, whereas the sleeve H has a plain bore. A spindle I is guided at its lower end in the sleeve H and engages with its screw-threaded upper end in the nut-like sleeve G . The spindle I is prevented from moving longitudinally in the sleeve H by means of stop 10 collars i , i^1 . J is a hand-wheel for screwing and unscrewing the spindle I in the nut-like sleeve G .

It will be readily perceived that the indentations produced at two opposite points 15 f , f^1 of the article being tested, are produced with one and the same apparatus under identical conditions of pressure, temperature and duration of indentation of the indenting device. The comparison between 20 the two indentations will therefore furnish very clear indications as to the relative hardness of the opposite surfaces of the article, and, from this fact, upon the homogeneity 25 of the metal in the region that has been tested.

In the construction form of the apparatus shown in Figs. 3 to 6 which illustrate an apparatus for applying the improved process for testing the hardness of a hollow article, 30 such as a shell, one of the jaws of the pincers is carried by an arm C so shaped as to be capable of entering the hollow article, that is to say in the present example, or passing through the hole in the nose of the shell F . 35 This arm C while being sufficiently strong, may have a slight degree of springiness; it is formed on or carried by a bracket K mounted on a bed L . It is combined with a cradle M for supporting the shell to be tested. The axis of this cradle is located in a longitudinal axial plane of the arm C . The 40 said cradle may be formed on a stem m slideable in a foot plate M^1 which is in its turn slideable in the bed L in the longitudinal axial plane of the arm C . M^2 is a spring bearing at one end against the underside of a shoulder on the platform M and at its other end against the foot plate M^1 . This 45 spring is calibrated in such a manner that when the cradle is brought to the desired point, the said spring will approximately 50 balance the action of the weight of the shell F upon the jaw formed on the end of the arm C .

55 The other jaw of the tongs or pincers is constructed as follows: N is a screw to the end of which there can be alternately fixed the ball-holder E or the die-holder. This screw is movable in a nut O formed at an intermediate point of a lever P located in a plane at right angles to the longitudinal axial plane of the arm C . This lever is fulcrumed at one end on an axle pin p mounted in the framing of the apparatus. The force 60 required for producing the simultaneous in-

dentations, is applied at the opposite end or at any other suitable point of the lever P by any known means.

By way of example the drawing shows a simple means consisting in suspending near 70 the free end of the lever P , a rod Q provided with a retaining collar or shoulder q , upon which a variable number of heavy disks R can be engaged.

The lever P may be guided between uprights S . Between these uprights there may be located a retractable support T . This support may be constituted for instance by a plate mounted on the end of a rack t working between plain supports t^1 and a pinion t^2 loose on an axle pin t^3 carried by the said uprights S .

Normally the action of the weights R will be balanced by the support T which is maintained in engagement by an actuating pinion $85 T^1$ fixed to a ratchet wheel T^2 with which a pawl T^3 is adapted to be engaged.

In order to raise the lever P , the pinion T^1 will be operated by means of a hand-wheel U and gear $u-u^1$, after having first placed 90 the pawl T^3 in its initial position.

For the purpose of producing the simultaneous indentations by means of the pincers arranged in this manner, first the upper ball holder E is brought into contact with the 95 shell. It will then be necessary to move away the support T by disengaging the pawl T^2 and thus allow the weight R to come freely into action. The support T will move away by its own weight.

Figs. 7 and 8 illustrate a modification of the preceding apparatus designed more particularly for ascertaining the hardness of the inner bottom end of a hollow article, such as for instance the base of a projectile.

In this example, the projectile or other hollow article to be tested, is supported by a platform M carried by rods m slideable in a foot-plate M^1 which may be fixed at a varying distance from the bed L . M^2 are 100 springs bearing against the foot-plate M^1 and the platform M ; they serve to balance practically the weight of the article under test. One of the ball holders E is mounted on the end of an arm C fixed to the foot-plate M^1 in such a manner that the said ball holder E shall be capable of projecting through a central orifice in the said foot-plate. The other ball holder is mounted on the lower end of an arm N^1 which is pivoted by means of a pin n to a screw N . This screw N is, as in the preceding example, adapted to work in a nut O provided at an intermediate point of a lever P . This lever P is, as in the example shown in Figs. 125 3 to 6, fulcrumed at one end on an axle pin p and is adapted to receive at its other end the effort required for producing the simultaneous indentations.

The apparatus is completed by a simple 130

means which allows of bringing different regions of the bottom of the hollow article between the two jaws of the pincers, the latter occupying an eccentric position relatively to the axis of the said article as shown. To a clamping ring V located at a suitable point in the length of the projectile there is jointed a lever V¹ adapted to bear upon the outer surface of the shell. The power required for moving the shell around its axis by means of the lever V¹, is reduced by arranging the latter to bear by means of a roller V² upon a circular track V³ located on the framing of the apparatus. The shell is guided vertically for instance by means of a suitably calibrated sleeve X.

One or more guiding rollers X¹ whose axles are mounted on the framing are provided for the purpose of guiding the shell so as to keep it upright for centering it in the sleeve X in placing the shell upon the supporting platform.

After the external and internal indentations have been produced simultaneously by means of the improved apparatus, they may be reproduced in relief in a plastic material, by dismounting the ball holders E—e and replacing them by dies, that is to say, by similar holders bearing a plate of lead or other plastic material. The pressure for effecting the simultaneous moldings of the two indentations may be produced by means of the same weight R on the lever P, acting if desired for a shorter time, or by means of a suitably reduced weight.

It is to be understood that the improved process and apparatus for producing and then observing simultaneous indentations formed in varying regions of a test article under identical conditions of pressure, temperature and duration of indentation, while furnishing on one hand valuable indications as to the constitution of the test article, are also capable of furnishing at the same time indications as to the apparatus for tempering or treating, or as to the nature of the metal; if the operations are carried out with a standard test piece or on a verified test piece. This invention can thus furnish simple and practical means for regulating a manufacture, because it allows of modifying according to the indications obtained, the apparatus for tempering or treating, as well as the nature of the metal.

Having now described my invention what I claim as new and desire to secure by Letters Patent is:—

1. The process for testing the hardness of metal plates, walls, and the like which consists in subjecting the same at opposite points on opposite sides of the plate or wall to be tested to the simultaneous action of indentation means impelled by equal forces and adapted to produce indentations increasing in dimension with increase of penetration and then measuring the dimensions of the indentations to determine the degree of homogeneity of the metal at the portion tested. 70

2. In an apparatus for testing the hardness of a test article by producing indentations in opposite surfaces of said article, the combination of a pair of tongs, a removable holder in the jaw of each tong, 75 an indenting body, such as a steel ball, in said holder, and mechanism acting upon the tails of said tongs for pressing said holders containing said indenting bodies against opposite surfaces of the test article. 80

3. In an apparatus for testing the hardness of a test article by producing indentations in opposite surfaces of said article, the combination of a pair of tongs, a removable holder in the jaw of each tong, an 85 indenting body, such as a steel ball, in said holder, an internally screw-threaded sleeve on the tail of one tong, and a plain bore sleeve on the tail of the other tong, a partly screw-threaded spindle engaging said sleeves, and 90 a device for rotating said spindle so as to move the indenting jaws toward each other.

4. In an apparatus for testing the hardness of metal walls and the like by producing indentations in opposite surfaces of said wall, the combination of oppositely disposed holders for receiving hardness testing elements, said testing elements being adapted to be simultaneously operated by equal forces to produce indentations increasing in dimension with increase of penetration, and means for moving one of said holders into testing position with respect to the other. 100

In testimony whereof I have affixed my signature in presence of two witnesses.

EUGÈNE SCHNEIDER.
